UNITED STATES PATENT OFFICE.

JOHN R. GRUETTER, OF CLEVELAND, OHIO, ASSIGNOR TO THE LOEW MANUFACTURING COMPANY, OF CLEVELAND, OHIO, A CORPORATION OF OHIO.

BOTTLE-CLEANING APPARATUS.

1,110,927.

Specification of Letters Patent. Patented Sept. 15, 1914.

Application filed March 30, 1910. Serial No. 552,386.

To all whom it may concern:

Be it known that I, JOHN R. GRUETTER, a citizen of the United States, residing at Cleveland, in the county of Cuyahoga and State of Ohio, have invented a certain new and useful Improvement in Bottle-Cleaning Apparatus, of which the following is a full, clear, and exact description, reference being had to the accompanying drawings.

10 This invention relates to an apparatus for cleaning bottles, and more particularly to an apparatus of the rotary type of bottle cleaner and washer such as shown in Patent #950,934, issued March 1, 1910.

15 The general objects of the invention are to provide an apparatus of this character which shall be efficient in operation, insuring thorough and rapid cleaning of the bottles; to provide such apparatus with efficient 20 means for brushing or cleaning the exteriors of the bottles during their transit in the rotating or moving carrier; to provide means whereby the bottles may be automatically removed from the machine at the end of the 25 cleaning operation; also to provide means whereby the supply of water to the brushers or rinsers, which are temporarily adjacent to the bottle-removing means, may be automatically cut off.

30 With the foregoing objects in view, the invention may be defined further and generally as consisting of the combinations of elements embodied in the claims hereto annexed and illustrated, in one exemplification, in the drawings forming a part hereof, wherein,—

Figure 1 represents a side elevation of a bottle-washing machine constructed in accordance with my invention; Fig. 2, a vertical sectional view taken through the center of the machine shown in the preceding figure, the machine being shown on an enlarged scale and the bottle-removing device being omitted; Fig. 3 represents a horizontal sectional view corresponding to the line 3—3 of Fig. 2; Fig. 4 represents a top plan view of the devices for brushing or cleaning the exteriors of the bottles; Figs. 5, 6 and 7 are details, respectively, in front elevation, top plan view and vertical section of the exterior brushing device; Fig. 8 represents a top plan view of the apparatus shown in Fig. 1; Fig. 9, a detail of the base of my apparatus; Fig. 10, an enlarged sectional detail corresponding to the line 10—10 of Fig. 2; Fig. 11, an

enlarged vertical sectional view through the water supply and cut-off chamber; Fig. 12, a vertical sectional detail taken through the devices for cleaning the inside of a bottle; and Fig. 13, an enlarged sectional detail of the means for supplying water to the interior of a bottle.

The invention shown herein comprises generally a bottle-supporting frame or carrier consisting of a pair of spaced rings, one of said rings having bottom clamps and the other having mouth clamps for the bottles; a brush-supporting and operating frame consisting of an upper guide ring located below the lower ring of the bottle-supporting frame with means whereby brushes may be rotated and be reciprocated through said ring and into the bottles thereabove; means for rotating the bottle and brush-carrying frames at uniform speed; means whereby the brushes will be reciprocated during such rotation; means whereby the bottles will be subjected, during a portion of their period of rotation, to the action of external brushing means and will be rotated, during the operation of the external brushing means, in a direction opposite to that in which such brush is driven; means for automatically removing the bottles from their carrier or frame; means for automatically supplying water to the bottles during the rotation of the carrier frame; and means for automatically cutting off the supply of water to the bottles and the cleaning means when the bottles reach the removing apparatus.

Describing the parts by reference characters, 1 denotes the base of the apparatus, said base being provided with an inlet passageway 2 leading to a central passageway 3. The base is provided with an annular trackway 4, on which the rotating frame work is supported by means of rollers, to be described hereinafter.

5 denotes a standard projecting upwardly from the base at one side thereof and having at its upper end an arm 6 having forks 6^a extending over and beyond the top of the apparatus.

7 denotes a vertical drive shaft having its upper end journaled in the arm 6, as shown at 8, and its lower end journaled in the sleeve 9 supported by the base, the lower end of the shaft being supported on the sleeve by means of a ball-bearing 10. The upper end of the shaft 7 is provided with 110

a pulley 11, by means of which it may be driven, and the shaft is provided with a bevel pinion 12 by means of which its rotation is transmitted through the bevel gear 13 to a shaft 14 supported in bearings 15 and 16. The shaft 14 extends outwardly from the central portion of the apparatus and is provided with a bevel pinion 17 meshing with the bevel gear #18, the latter gear being rigid with the shaft 19. This shaft 14 has its lower end supported in the base frame 1 and is provided with gears 20 and 21 and with sprocket wheels 22 and 23. The gears 18 and 20 and the sprocket wheel 23 are shown as resting on bearings provided in brackets 24, 25 and 26, the first-mentioned bearing being arranged to take the thrust of the shaft.

Surrounding the shaft 7 is the sleeve 27. The upper and lower ends of the sleeve are of somewhat larger internal diameter than the external diameter of the shaft to receive suitable shaft sleeves or bearings 28-29, the latter sleeves providing anti-friction bearings between said sleeve and the shaft 7.

30 denotes the hub of a carried member which is carried by and rigid with the sleeve 27. Radial arms 31 connect said hub 30 with the outer ring 32. This ring is provided with a suitable number of vertically-extending perforations for the shafts of the clamps for the bottle bottoms.

33 denotes the hub of a similar carrier member, located below the member just described. This hub, however, is provided with an internal thread adapted to mesh with an external thread 34 on the sleeve 27 and is provided also with a key 35 by means of which, and the threaded construction referred to, the hub may be adjusted along the sleeve and may be secured to the latter. Radial arms 36 connect this hub with the external ring 37, which is provided with perforations for the reception of the sleeves which carry the bottle mouth supports and which receive the internal brushes. The vertical adjustment provided for the lower carrier member enables the latter to be moved toward and from the upper member to accommodate the distance between the members to varying lengths of bottles. For the purpose of securing the lower member in its adjusted position, I provide a pair of clamping rings 38 and 39 mounted upon the sleeve 27 above and below the hub 33, respectively. Each of these rings may be made in the form of a hand-wheel, for convenience of manipulation.

40 denotes the hub of a third frame member, located below the former members and rigidly mounted on the sleeve 27. This hub is also connected by radial arms 41 with an external ring 42 having apertures reg-

istering with the apertures in the ring 37 and coöperating with the latter to form supports for the brush spindle sleeves. Below the last-mentioned frame member is a large gear having a hub 43 rigid with the shaft 7. This gear is preferably of the spur gear type, as indicated at 44, and is adapted to rotate the spindles of the internal brushes.

Below the ring 37 is mounted a pan 45, said pan having flanged apertures for the reception of the brush spindle sleeves and being provided with a drain pipe 46. The rings 32 and 37 carry the supports or clamps for the bottoms and mouths of the bottles to be washed. These supports or clamps and the construction and manner of operation of the internal brushing and rinsing devices are shown more particularly in Figs. 2 and 12.

47 denotes the shaft or stem of one of the bottle bottom clamps. This shaft projects through the ring 32 and is shown as having a head 48 at its upper end, for the purpose of retaining thereon an arm 49 having a roller 50 applied thereto. Below the ring 32 the shaft 47 is provided with a frusto-conical clamp 51 for the bottom of a bottle, said clamp having a neck 52 journaled on the shaft 47. A pinion 53 surrounds said neck and is secured thereto, as by pins 54. The shaft 47 is vertically slidable relatively to the ring 32, and suitable means is provided to prevent the rotation of the arms 49, the means here illustrated comprising guide pins 47^a carried by the arms and projecting into suitable apertures in the ring. Through each aperture in the ring 37 there projects a sleeve 55, said sleeve having a horizontal flange 56 by which it is supported on top of the ring 37 and having an upwardly-flared mouth 57 for the reception of the mouth of a bottle 58. It will be observed that the mouth of the bottle barely rests within the mouth or seat 57, enabling it to be removed from the latter with comparative ease. The sleeve 55 will be retained in place in the ring 37 by means of a set screw 59.

The apertures in the ring 42 correspond in position to those in the ring 37 and are provided each with an annular seat for the lower end of the sleeve 55. This annular seat may be provided between the lower end of an inner sleeve 60 and the lower end of an outer sleeve 61, which may be fitted within the aperture of the ring 42, the sleeves 60 and 61 being connected together by means of screw-threads, as shown at 62. The sleeve 60 forms a close fit with the interior of the sleeve 55 and, when the parts are in the position shown in Fig. 12, which is the position they occupy in operating upon bottles of maximum length, the lower end of the sleeve 55 will be substantially at the bottom of the annular space between the sleeves 60 and 61.

60 and 61, and the upper end of the sleeve 60 will be at the upper end of the cylindrical interior of the sleeve 55. It will be noted that the upper portion of the interior of the sleeve 55 tapers inwardly, as shown at 5 63, forming, at the upper end of such tapered portion, a guide for the brush spindle. The ring 42 is of considerable vertical extent and the apertures which extend from the top to the bottom thereof receive the necks 64 of pinions 65 by which the brush spindles are driven, the ring being projected downwardly below the pinions to provide bearings 66 for said pinions. These 10 pinions are adapted to mesh with the teeth 44 of the large gear carried by the shaft 7, and the sleeves 61 conveniently constitute upwardly-projecting necks of said pinions, the teeth of the pinions being preferably 15 shielded by guards 65^a.

Below the apertures in the ring 42 there are located the brush spindle carriers 67. Each of these is connected, by a pair of vertical rods 68, with the lower part of the ring 42, as shown at 68^a, the brush carriers being provided with sleeves 69 slidable along said rods. Each spindle carrier is provided with a roller 70 adapted to engage a cam track 71 carried by the base 1, and of 20 any contour suitable to reciprocate the carriers 67 and cause a reciprocation of the brushes a distance at least the length of the bottles thereabove and to repeat such operation as often as desirable for each 25 rotation of the apparatus. Each carrier is provided with a lateral passageway 72 communicating, by a flexible pipe 73, with a water chamber formed in the center of the base and supplied from the passageway 2.

30 The passageway 72 communicates with the chamber 74, which chamber provides a rotary bearing for the lower end of a brush spindle. The brush spindle is shown at 75, and is similar to that shown in Patent 35 #950,934. The spindle is provided with a vertical passageway therethrough, as shown at 76, and has at its upper end a brush 77. The lower end of the brush spindle is supported by a nut 78 threaded thereonto, said 40 nut having upper and lower surfaces reversely tapered or beveled, as shown at 79. The lower beveled surface of the nut forms a bearing with the corresponding beveled surface 80 of the chamber 74. The 45 nut and spindle are retained in place by means of a suitable gland 81 surrounding the spindle 75 and threaded into the carrier above the chamber 74. The lower end of this gland is preferably tapered, as shown 50 at 82, to correspond to the tapered upper surface of the bearing nut 79. The spindles are each provided with a key-way 75^a by which they are slidably keyed to the pinions 65.

55 For the purpose of brushing the exteriors

of the bottles during their rotation with the carrier, the following construction is provided:—The bracket 25 is provided with a track 83 formed by downwardly-projecting flanges at its inner end, and the bracket 26 70 is provided with a similar track 84 formed by upwardly-projecting flanges at its inner end. These tracks are curved, the curves being concentric with the shaft 7 and being located in close proximity to the exterior 75 of the bottles 58. The brush which I employ consists of an upper chain 85 and a lower chain 86 adapted to be engaged by the rear or outer teeth of the sprockets 22 and 23, the corresponding links of said 80 chains being connected by strips 87, preferably of wood, the strips being shown as secured to flanges 88 and 89 projecting, respectively, from the corresponding side plates of the chains 85 and 86. Each of 85 the strips 87 is provided with a suitable number of bunches of bristles 90. The brackets 25 and 26 are of considerable lateral extent and each is provided near its end with a shaft, said shafts being shown 90 at 91 and 92. One of these shafts, as 92, will be preferably mounted in boxes 93, the boxes being slidably supported in suitable 95 bearings formed in the brackets, and the boxes being pressed outwardly by means of springs 94. The shafts 91 and 92 are provided with sprocket wheels corresponding in vertical location to the sprocket wheels 22 and 23, the lower sprocket wheels being shown in Fig. 3 at 95 and 96.

100 For the purpose of driving the chain and brush in the same direction as the bottle carrier and in the reverse direction from the rotation of the bottles on their axes, the gear 20 on shaft 19 meshes with a gear 97 105 on an intermediate shaft 98 which is connected by a chain 99 and sprocket 100 with shaft 91. By this arrangement, the rotation of the shaft 19 is transmitted to the shaft 98 and the latter is connected to shaft 91, 110 which drives the shaft 92 and the brush in a direction opposite to the rotation of the bottles on the carrier.

115 For the purpose of automatically removing the bottles, I provide a cam 101, carried by the outer ends of the arms 6^a and arranged to engage the rollers 50 and move the bottom clamps 51 away from the bottoms of the bottles, together with means adapted to engage the bottles at this time and automatically remove the same from the carrier frames. For the purpose of so removing the bottles after the clamps have been lifted, the following construction is provided: The ring 32 is provided with a plurality of U-shaped 120 frames comprising a pair of downwardly-projecting arms 102 connected at their lower ends by a curved cross bar or cam 103, the cross bars being arranged in such manner that, assuming the machine to be rotating in 125 130

the direction indicated by the arrows and the movement of a bottle to be arrested, each cross bar will engage the body of the bottle and tend to move the bottle outwardly. The 5 ring 37 is provided with a plurality of horizontally-extending curved arms or cams 104, projecting in proximity to the necks of the bottles and of substantially the same contour as the cross bars or cams 103 and operating 10 in like manner upon the necks of the bottles to deflect the bottles outwardly when their progress is arrested while the bottle-carrier continues its rotation in the direction of the arrows shown on Fig. 3.

15 Coöperating with the cam surface provided by the parts 103, 104 is the bottle arrester and remover. This arrester and remover is located on the side of the apparatus opposite the brush which operates upon the exteriors of the bottles and is near the arm 6^a which supports the elevated end of the cam 101. This arrester and remover comprises a pair of upper rails 105 and a pair of lower rails 106. The farther rail of each 20 pair (referring to the direction of rotation of the bottle-carriers) projects into the path of the moving bottles in position to be engaged thereby. The corresponding ends of the other rails do not project inwardly to 25 such an extent and provide a clearance for the bottles. The inner portions of the upper rails are conveniently supported by means of a frame 107, which may be carried by a bracket 108 which in turn may be supported 30 by a suitable frame member 109 carried by the arms 6^a. The inner portions of the rails 106 are supported from the frame 107 by means of the arms of a bracket 110 carried by a bolt 111 projecting through the base of 35 the frame 107 and threaded thereto. By the adjustment of the bolt the lower rails may be adjusted vertically to accommodate them to the position of the lower ring 37 and the length of the bottles carried thereby. The 40 rails 105, 106 are preferably curved in the manner shown and are supported at suitable intervals by means of additional frames 112 having the rails 105 secured to the upper ends thereof and provided with yokes 113 45 carried by bolts 114 which are threaded into the bases of the frames 112 and are adjustable in the same manner as the yoke 110. The rails 106 are spaced apart a sufficient 50 distance to receive the neck portions of the bottles and the rails 105 are spaced a sufficient 55 distance to receive the bodies of the bottles therebetween.

To assist in retaining the bottles in vertical position on the rails of the remover, one of the rails 105 will be provided with a 60 suitable number of spring fingers 115 extending inwardly and forwardly (or toward the direction of travel of the bottles) therefrom, said springs being covered with rubber

or similar material to prevent injury to the 65 bottles.

Coöperating with the exterior brush is a segmental gear 116 which is adapted to engage the gears or pinions 53 attached to the bottle bottom clamps and thus rotate the 70 bottles in a direction the reverse of that imparted to the brush. For the purpose of cushioning the impact of the pinions against this gear, the end 117 of the segmental gear which the bottles are approaching is pivotally connected to the body of the gear, as shown at 118, and a spring 119 is applied to such pivoted end, which spring provides means yieldingly holding such end in operative relation to the pinions of the approaching 75 bottle clamps.

Coöperating with the bottle remover is the means for automatically cutting off the supply of water to the brush spindles which are temporarily in operative relation to such 80 remover. This means is shown in Figs. 2, 10 and 11, and comprises a segmental valve 120 mounted within the rotating hub 121 which contains the chamber 122 from which water is supplied to the flexible tubes 73 85 through the ports 123. This segmental valve 120 may be conveniently carried below a packing ring 124 interposed between the hub 121 and the sleeve 9, the valve being held to its seat against the inner surface of the hub 90 by means of springs 125 engaging the beveled ends of the segmental plate and lugs 126 projecting downwardly from the ring 124.

In operation, the shaft 7 is rotated from 100 the pulley 11 and its rotation is imparted to the rings 32, 37 and 42 through the shafts 14, 19, pinion 21, pinion 127 mounted on the base 1, and the gear 128 having the hub 121. This gear is supported by means of the 105 rollers 129 mounted between the annular flanges 130 carried by the base. To keep the rollers separated, their pins or shafts are mounted in annular steel bands 131 mounted within the flanges 130. The rotary 110 motion of the gear 128 is transmitted through the rods 68 to the spindle carriers 67 and the ring 42, and the motion of the latter ring is transmitted through the sleeve 115 27 to the bottle-carrying rings 32 and 37. The operator stands at a point just beyond or to the left of the bottle remover and inserts the bottles between the clamps 51 and 57 while the former clamps are held elevated by the cam 101. As soon as the rollers 50 ride off this cam, the clamps 51 are brought into engagement with the bottoms of the bottles by gravity. The brush spindles are rapidly rotated by the engagement of their pinions 65 with the gear teeth 44, 125 and the brushes are reciprocated within the bottles by the action of the cam 71 on the rollers 70, water being supplied to the hol-

low spindles by the flexible pipes 73. When the clamps 51 reach the segmental gear 116, the bottles are rapidly rotated and the exteriors of the bottles are brushed, the bottles being rotated in a direction the reverse of that in which the brush is driven. At about the time the bottles and their clamps reach the cam 101 the supply of water to their flexible tube 73 is automatically cut off by the valve 121. The clamps 51 are elevated by the cam 101, the bottles are successively engaged by the inwardly-projecting ends of the rails 105—106 and are deflected outwardly between and along said rails by the cam-like members 103, 104.

During the operation of the machine, the brushes are withdrawn into the sleeves 60 at least when they are in the vicinity of the bottle remover and remain in such sleeves for a considerable period of time. These sleeves, being formed with the necks of the pinions 65, are driven at the same rate of speed as the spindles and hence the brushes are protected against wear by friction by rotation within said sleeves.

Should occasion occur for adjusting the machine to accommodate different lengths of bottles, such adjustment is assured through the adjustability of the ring 37 on the sleeve 7 and the telescopic connection between the sleeves 55 and 60, and this adjustability does not interfere with the operation of the bottle remover, as the lower rails 106 may be adjusted correspondingly. The water discharged from the bottles flows into the pan 45 and is in turn discharged from the latter by the drain pipe 46.

Having thus described my invention, what I claim is:

- 40 1. In a bottle cleaning apparatus, the combination of a carrier, means for rotating the same, an endless brush having a concave surface located in the path of travel of said carrier and of the bottles thereon, means for driving said brush, and means for automatically rotating the bottles on the carrier so as to cause their surfaces to move in the same direction as the portion of the exterior brush adjacent thereto during the entire time of their treatment thereby.
- 45 2. In a bottle cleaning apparatus, the combination of a bottle carrier, means for driving the same, an endless brush having a surface presented toward said carrier, means for driving said brush, gears whereby the bottles on said carrier may be rotated, and a segmental gear adjacent to said brush and arranged to engage the bottle-rotating gears.
- 50 3. In a bottle cleaning apparatus, the combination of a bottle carrier, means for driving the same, an endless brush having a surface presented toward the carrier, means for driving said brush, gears whereby bottles on the carrier may be rotated, and a segmental gear located adjacent to said brush

and having a yielding end portion adapted to engage the bottle-rotating gears.

4. In a bottle washing apparatus, the combination of a bottle carrier, means for driving the same, a brush located in operative relation to the carrier and arranged to operate on the exteriors of the bottles carried thereby, gears whereby bottles on the carrier may be rotated, a gear located adjacent to the brush and arranged to engage the bottle-rotating gears, and means whereby the engagement between the bottle-rotating gears and the latter gear may be cushioned.

5. In a bottle cleaning apparatus, the combination of a carrier, means for rotating the same, a flexible endless brush arranged to present a concaved surface toward the carrier, a gear adjacent to said brush and having a pivoted end, a spring for said end of the gear, and gears for bottles on the carrier arranged to engage the pivoted end of the first-mentioned gear.

6. In a bottle cleaning apparatus, the combination of a bottle carrier, means for rotating the same and a brush for cleaning the exterior of the bottles on said carrier, said brush comprising a pair of chains, members connecting said chains, brushes carried by said members, the chains being arranged to present a concaved surface toward the bottle carrier, and means for driving said chains.

7. In a bottle cleaning apparatus, the combination, with a circular bottle carrier having means for supporting bottles in a position parallel with its axis, and means for rotating said carrier about its axis, of an endless brush supported by the apparatus frame at the side of said carrier, means carried by said frame and imparting to the portion of said brush adjacent to said carrier a curvature substantially the same as that of said carrier, and means for driving said brush.

8. In a bottle cleaning apparatus, the combination, with a fixed frame and a rotatable bottle carrier supported by said frame, said carrier having bottle receiving sockets, of spaced segmental tracks carried by said frame, said tracks being substantially concentric with said carrier, an endless brush having guiding portions engaging said tracks whereby it is given a curvature substantially the same as that of said carrier, and means for operating said brush.

9. In a bottle cleaning apparatus, the combination of an upper and a lower carrier member, bottom clamps supported by one of said members and mouth clamps supported by the other of said members, means whereby the distance between said members may be varied to accommodate varying lengths of bottles, hollow brush spindles, means for reciprocating the same through the clamps for the bottle mouths, the latter clamps having

each a sleeve formed therewith, and sleeves telescopically fitted within the former sleeves and surrounding the hollow spindles and driven therewith, whereby said members can be adjusted toward and from each other without uncovering said spindles.

10. In a bottle washing apparatus, the combination, with a bottle carrier having fixed sockets in its upper part and vertically movable sockets in its lower part adapted to receive respectively the bottoms and tops of bottles whereby the same are supported in an inverted position on said carrier, of sleeves extending downwardly from below the mouths of the bottles on the carrier, brush spindles, means for reciprocating said spindles into the bottles on the carrier and for withdrawing the brushes from the bottles into the sleeves, a gear connected with each of said spindles for rotating the same, and a sleeve telescoping with said first sleeve and having a driving connection with one of said gears.

11. In a bottle washing apparatus, the combination of a bottle carrier, bottom and mouth clamps on said carrier, means for adjusting said mouth clamps toward and from said bottom clamps, a sleeve extending from each mouth clamp, brush spindles, means for reciprocating said spindles through said sleeves and within the bottles supported thereabove, a gear having a sliding connection with each spindle, a sleeve surrounding each spindle and having a telescoping engagement with the corresponding clamp sleeve, and a connection between each of said gears and its corresponding sleeve.

12. In a bottle washing apparatus, the combination, with a fixed bottle bottom support, of a bottle mouth clamp having a downwardly projecting sleeve, means for shifting said mouth clamp toward and from said bottom clamp to grip bottles therebetween, a sleeve telescoping within the former sleeve and supported at a fixed distance from said bottom support, a brush spindle, a gear having a sliding connection with said spindle, means for reciprocating said spindle through the second sleeve and through the mouth clamp, and a driving connection between such gear and the second sleeve.

13. In a bottle cleaning apparatus, the combination of an upper and a lower carrier ring, means for rotating the same, an upper and a lower pair of rails arranged to receive, respectively, the bodies and necks of bottle therebetween, said rails extending away from the apparatus and the farther rail of each pair projecting into the path of movement of the bottles, and cam members on said carriers adapted to coöperate with the bodies and necks of the bottles thereon to force the bottles between the rails when so engaged by the farther rails.

14. In a bottle cleaning apparatus, the

combination of a carrier for the bottles, a receiver for bottles in operative relation to said carrier and having a track for such bottles, said receiver having means arranged to intercept the bottles on the carrier, and yielding members projecting from the receiver into the path of the bottles thus forced therealong.

15. In a bottle cleaning apparatus, the combination of a movable carrier, bottle clamps associated with said carrier, a receiver for cleaned bottles in operative relation to said carrier and having a fixed rigid deflecting arm arranged to intercept the bottles on the carrier, means associated with the carrier for forcing the bottles thus intercepted into the receiver, and means operative by the movement of the carrier for automatically unclamping the bottles when thus intercepted.

16. The combination, with a bottle carrier, of means for cleaning bottles in transit on said carrier, a receiver for cleaned bottles, stationary means projecting from said receiver and arranged to intercept the bottles on the carrier, and one or more cam devices for each bottle, said devices being associated with said carrier and arranged to force the intercepted bottles, by the movement of the carrier, into the receiver.

17. In a bottle cleaning apparatus, the combination of a carrier comprising a pair of members, means whereby one of said members may be adjusted toward and from the other, a bottle arrester and remover arranged in operative relation to the carrier and comprising a pair of spaced members for the bottles, and means whereby one of the latter members may be adjusted toward and from the other.

18. In a bottle cleaning apparatus, the combination of a pair of vertically-spaced carrier members, means whereby one of said members may be adjusted toward and from the other, a bottle arrester and remover arranged in operative relation to said carrier members, said arrester and remover comprising a pair of vertically-spaced rails, and means whereby one pair of rails may be adjusted toward and from the other.

19. In a bottle cleaning apparatus, the combination of an upper and a lower carrier member, a rotary support for said members, said support being provided with an external thread and one of said members having a hub provided with an internal thread whereby it may be adjusted along said rotary support, and a nut mounted on each side of said hub and threaded upon said support.

20. In a bottle cleaning apparatus, the combination of a shaft, means for rotating the same, a sleeve journaled on said shaft, a pair of bottle-carrier members on said sleeve, said sleeve having a threaded portion and

one of said members having a hub provided with an internal thread engaging the thread on said sleeve, means for locking said hub in position, a brush carrier rotatable with 5 said members, brush spindles associated with said carrier, a pinion on each spindle, a gear on said shaft for rotating said spindles, and connections for driving said sleeve from said shaft.

- 10 21. In a bottle washing apparatus, the combination, with a fixed support and a rotatable frame, carried thereby, said frame comprising vertically spaced upper and lower members, said upper member having 15 seats for the bottoms of inverted bottles and said lower member having vertical apertures therein, of a hollow sleeve within each aperture and communicating at its upper end with a bottle mouth clamp, means for shifting said sleeve toward and from said member, a second sleeve journaled in said frame and telescopically engaging said first sleeve, a pinion secured to said second sleeve, a gear carried by said support concentric with said frame and meshing with 20 said pinion, a guide member carried by said frame below said lower member, a carrier 25 slideable along said guide member and having a liquid passage therein, a hollow shaft journaled to said carrier and projecting into 30 said sleeves, said shaft being longitudinally movable relatively to said pinion but non-rotatable relatively thereto and also having 35 its interior in communication with the liquid passage in said carrier, a brush carried by the upper end of said shaft, a cam track carried by said support and adapted to raise and lower said carrier during the rotation of said frame so as to project said brush above said sleeves and then retract it 40 therewithin, means for supplying cleansing fluid to said carrier during the time that the same is in elevated position, and means for removing bottles from said frame during the time that said carrier is in depressed 45 position.

In testimony whereof, I hereunto affix my signature in the presence of two witnesses.

JOHN R. GRUETTER.

Witnesses:

J. B. HULL,
CHAS. H. WEIR.

22. In a bottle washing apparatus, the 45 combination, with a fixed support and a rotatable frame, carried thereby, said frame comprising vertically spaced upper and lower members, said upper member having seats for the bottoms of inverted bottles and 50 said lower member having vertical apertures therein, of a hollow sleeve within each aperture and communicating at its upper end with a bottle mouth clamp, means for shifting said sleeve toward and from said 55 upper member, a second sleeve journaled in said frame and telescopically engaging said first sleeve, a pinion secured to said second sleeve, a gear carried by said support concentric with said frame and meshing with 60 said pinion, a guide member carried by said frame below said lower member, a carrier 65 slideable along said guide member and having a liquid passage therein, a hollow shaft journaled to said carrier and projecting into 70 said sleeves, said shaft being longitudinally movable relatively to said pinion but non-rotatable relatively thereto and also having its interior in communication with the liquid passage in said carrier, a brush carried by the upper end of said shaft, a cam track carried by said support and adapted to raise and lower said carrier during the rotation of said frame so as to project said brush above said sleeves and then retract it 75 therewithin, means for supplying cleansing fluid to said carrier during the time that the same is in elevated position, and means for removing bottles from said frame during the time that said carrier is in depressed 80 position.
